Filed Feb. 20, 1973, Ser. No. 334,041

Term of patent 14 years

Int. Cl. D12—02

U.S. Cl. D12—25

FIG. 1 is a perspective view of a storage cart, showing my design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof; and

FIG. 7 is a rear elevational view thereof.

The broken lines in the drawing are for illustrative purposes only.

The parallel rows of dashed lines on the rear vertical panel in FIGS. 1, 6 and 7 represent narrow slots.

I claim:

The ornamental design for a storage cart, as shown and described.
